UNITED STATES PATENT OFFICE.

CHRISTOPHER L. STANGE, OF ST. LOUIS, MISSOURI.

DESIGN FOR A LINGERIE BUTTON.

Application filed April 3, 1925. Serial No. 12,998. Term of patent 3½ years.

To all whom it may concern:

Be it known that I, CHRISTOPHER L. STANGE, a citizen of the United States, residing in the city of St. Louis and State of Missouri, have invented a new, original, and ornamental Design for Lingerie Buttons, of which the following is a specification, reference being had to the accompanying drawing, forming part thereof.

Fig. I is a plan view of a lingerie button showing my new design.

Fig. II is a side elevation.

I claim:

The ornamental design for a lingerie button, as shown.

CHRISTOPHER L. STANGE.
